(57) **CLAIM**

The ornamental design for a folding motorized mobility device, as shown and described.

DESCRIPTION

FIG. 1 is a right side elevation view of a folding motorized mobility device showing our new design;

FIG. 2 is a right side elevation view thereof, with the seat deployed;

FIG. 3 is a right elevation view of FIG. 1;

FIG. 4 is a top plan view thereof;

FIG. 5 is a top plan view thereof, with the seat deployed;

FIG. 6 is a front right perspective view of FIG. 1;

FIG. 7 is a front right perspective view thereof in a completely folded position;

FIG. 8 is a front right perspective view thereof with the seat deployed;

FIG. 9 is a rear right perspective view of FIG. 1; and,

FIG. 10 is a rear right perspective view thereof with the seat deployed.

The broken lines shown in the drawings illustrate portions of the folding motorized mobility device that form no part of the claimed design.
